UNITED STATES PATENT OFFICE.

OTTO DE FRIES DION, OF NEW YORK, N. Y.

RAG-CLIPPING MACHINE.

1,261,368.

Specification of Letters Patent. Patented Apr. 2, 1918

Application filed March 20, 1917. Serial No. 156,169.

To all whom it may concern:

Be it known that I, OTTO DE FRIES DION, a citizen of the United States, and a resident of New York city, in the county of New

5 York and State of New York, have invented a certain new and useful Improvement in Rag-Clipping Machines, of which the following is a specification.

The present invention relates to stripping 10 machines adapted particularly for use in the preparation of rag material used in the manufacture of new material.

In the preparation of rag material, such 15 as woolens, for the manufacture of new woolen material, it is essential to remove all seams containing cotton and other foreign substances which are undesirable, and the present method of removing these cotton 20 seams is to cut the same from the rag material by hand.

It is an object of the present invention to provide a stripping machine by means of which the seams may be cut from the rag material quickly, and with but relatively 25 small waste.

A further object of the present invention is to provide a relatively simply constructed and easily operated machine which requires but little practice in the operation thereof 30 for applying the rag material thereto for the removal of the cotton seams.

The above, and various other objects and advantages of this invention will be in part described, and in part understood, from the 35 following detailed description of the present preferred embodiment, the same being illustrated in the accompanying drawings wherein:

Figure 1 is a transverse vertical section 40 taken through a portion of a table having the machine applied thereto.

Fig. 2 is a section taken transversely through one end of the machine on the line 2-2 of Fig. 1.

45 Fig. 3 is a similar view taken on the line 3-3 of Fig. 1.

Fig. 4 is a detail enlarged sectional view taken longitudinally through one end of the machine.

50 Fig. 5 is an end elevation of the machine as applied to a table.

Fig. 6 is a detail side elevation of one of the stationary cutters or knives employed.

Fig. 7 is a transverse section taken through the stationary knife on the line 7-7 of 55 Fig. 6.

Referring to these drawings, 10 designates a table of any adaptable construction upon which the machine of this invention is transversely mounted. Posts 11 are secured to 60 the opposite sides of the table 10 and rise therefrom a suitable distance, and are provided with extensions upon their lower ends which project beneath the bed of the table. Shafts 12 and 13 are journaled at their op- 65 posite ends in the posts 11, the shaft 12 being arranged in suitably spaced relation about the table 10, and the shaft 13 being arranged against the underside thereof.

The shafts 12 and 13 are connected to- 70 gether by gear wheels 14 located preferably at one side of the table 10, the gear wheel 14 being intermeshed to turn the shafts 12 and 13 simultaneously and drive the same at the same rate of speed. The gear wheels 75 14 also cause the shafts 12 and 13 to turn in opposite directions, and one of the shafts, such as the shaft 12, is provided with an ex- 80 tension 15 to which may be connected suitable driving mechanism for operating the machine.

The shaft 12 is provided, at opposite sides of the table 10, with pairs of feed rollers 16 and 17 which are suitably spaced-apart, and which coöperate with corresponding pairs 85 of feed rollers 18 and 19 arranged upon the lower shaft 13, and which projects upwardly through suitable slots formed in the bed of the table 10. The tops of the rollers 18 and 19 are spaced slightly above the upper sur- 90 face of the table 10 and are slightly spaced below the bottoms of the rollers 16 and 17 to receive cloth or the like between the super- posed rolls. The shafts 12 and 13 are also provided, between the pairs of rolls 16 and 18, with superposed intermediate feeding 95 rolls 20 and 21, the former being relatively small to provide a relatively large space between the rollers and thus accommodate ma- terial folded or creased in several thick- 100 nesses.

The shaft 12 is provided with a pair of

cutting disks 22 located at the opposite sides of the upper intermediate feeding roll 20, the cutter 22 being arranged between the feed rolls 16 and being of greater diameter than 5 the same. The table 10 is provided upon its upper face and immediately beneath the cutting disks 22 with stationary cutting blades or knives 23, the latter being of semi-circular or segmental form and having an attaching flange 24 across the straight edge of each 10 stationary knife. The flange 24 is provided with perforations 25 therethrough adapted to receive screws or the like for holding the stationary blades to the table 10. The rotary knives 22, and the stationary knives 23 are arranged in common vertical planes, and the rotary knives 22 are beveled at their marginal edges and at their outer opposite sides to interfit with the inner beveled marginal edges of the stationary blades 23. This 20 arrangement is shown to advantage in Figs. 1 and 4 particularly.

The shaft 12 is also provided, between the rollers 17, with a rotary cutting blade or 25 knife 26 which is beveled at opposite sides and which is of slightly greater diameter than the rollers 17.

A substantially arcuate guard plate 27 extends across the tops of the standards or 30 posts 11 and is curved downwardly toward the front of the machine and supported in such position by means of bracket arms or straps 28 which project forwardly from the standards 11.

35 In operation, rag material, such as a sleeve, may be folded or collapsed with the seams thereof arranged adjacent to the folds and run through the rollers 17 and 19 for cutting the sleeve into three sections by 40 means of the blade. Each section is now flattened and fed to the rollers 16 and 18 with the intermediate seams thereof registering with the intermediate rollers 22 and 21. The feed rollers 16 and 18 draw the 45 flattened strip of material in between the rotary knives 22 and the stationary knives 23 to sever the material at opposite sides of the machine. The spacing apart of the feed rollers 20 and 21 is such as to receive 50 the thickness of the seam therethrough and feed it simultaneously with the feeding of the outer portions of the strip.

It is of course understood that various 55 portions of garments may be treated in substantially the same manner as above described by the use of this machine, and that the material is thus cut into strips and the seams removed therefrom.

60 Preferably, the fixed blades 23 are arranged in slightly offset relation rearwardly of the machine from the vertical plane of the shafts 12 and 13 to engage the material in the rollers prior to the cutting action, the rollers thus holding the material taut and

the cutting action tending to stretch the 65 material and thus facilitate the cutting of the same.

It is of course understood that any number of feed rollers and cutters or knives may be used as is found convenient in the 70 use of the machine without departing from the spirit of this invention, and various other modifications and changes may be made in the details of construction of the above specifically described embodiment 75 without departing from the spirit of the invention, and being restricted only by the scope of the following claims.

I claim:

1. In a stripping machine, the combination of a pair of vertically spaced apart connected shafts adapted to turn in opposite directions, spaced-apart pairs of feed rollers mounted on the shafts, a pair of spaced apart intermediate feed rollers arranged between said pairs of rollers, a pair of cutting disks arranged upon one of the shafts at the opposite sides of the intermediate rollers, and a pair of stationary cutters arranged between said pairs of feed rollers at the 90 opposite sides of the intermediate rollers for coöperation with the rotary cutters. 85

2. In a stripping machine, the combination of a table, a pair of connected shafts arranged in superposed relation upon the table and adapted to turn in opposite directions, pairs of spaced-apart feed rollers mounted on said shafts, a pair of intermediate spaced apart feed rollers mounted on said shafts between the first pairs of rollers, fixed cutters arranged upon the table between said first pairs of rollers and at the opposite sides of the intermediate roller, and a pair of rotary cutters mounted on one of said shafts adjacent the opposite 100 sides of the intermediate rollers for coöperation with the stationary cutters. 95

3. In a stripping machine, the combination of a table, a shaft arranged beneath the table, a shaft arranged above the table, superposed pairs of spaced apart feed rollers mounted on said shaft and projecting through the table with the rollers of each pair spaced apart, a pair of intermediate feed rollers mounted on said shaft spaced 110 apart a greater distance than the rollers of said first pair of feed rollers and projecting through the table, a pair of cutting disks fixed to the upper shaft at the opposite sides of the adjacent intermediate roller and having opposite beveled marginal edges, and fixed arcuate cutters carried upon the upper face of the table at the opposite sides of the lower intermediate roller for coöperation with the cutting disks and provided with 115 oppositely beveled edges coöoperating with the edges of said disks. 120

4. In a machine for stripping rags hav-

ing seams therein, the combination of spaced apart pairs of feed rollers with the rollers of each pair spaced apart to receive a rag with the seam between the pairs of rollers, 5 a pair of seam feed rollers arranged between said first pairs of feed rollers and being spaced apart a greater distance than the roll-

ers of each of said first pairs to receive the seam, and cutters arranged between said first pairs of rollers at opposite sides of the 10 seam rollers to sever the rag at opposite sides of the seam.

March 16, 1917.

OTTO DE FRIES DION.
